COMBINED POWER PACK AND TOOTHBRUSH HOLDER

William J. Rakocy, Clifton, N.J., assignor to Ronson Corporation, Woodbridge, N.J., a corporation of New Jersey

Filed Sept. 10, 1965, Ser. No. 86,945

Term of patent 14 years

(Cl. D4—3)

FIG. 1.

FIG. 6.

FIG. 5.

FIG. 1 is a perspective view of a combined power pack and toothbrush holder showing my new design;

FIG. 2 is a front elevational view thereof;

FIG. 3 is a side elevational view thereof;

FIG. 4 is a rear plan view.

FIG. 5 is a top plan view thereof.

FIG. 6 is a bottom plan view.

The broken line showings of the toothbrush, toothbrush power handle, and electric cord are for illustrative purposes only.

I claim:

The ornamental design for a combined power pack and toothbrush holder, substantially as shown and described.
